METHOD FOR MAKING RETAINERS FOR
ANTIFRICTION BEARINGS

Carl A. Baden, Glenbrook, Conn., assignor to
Norma-Hoffman Bearings Corporation, Stamford Conn., a corporation of New York

Original application January 20, 1940, Serial No.
314,779. Divided and this application September 22, 1941, Serial No. 411,856

2 Claims. (Cl. 29—148.4)

This invention relates to a method for making an improved roller bearing retainer of the one piece type.

The purpose of this invention is to overcome the manufacturing objections of roller retainers now made, and the invention provides a method for making a roller retainer of the one piece type in which the rollers may be snapped into position without any material binding of the metal and when so snapped into position to be held therein.

The invention consists in a method of making roller bearing pockets in a solid ring retainer, which consists in first drilling circular openings radially from one side to the other side of said solid ring spaced circumferentially along the central line of the ring having a diameter equal to the diameter of the roller for which the retainer is intended, then broaching the ring to form the circular opening into an opening having straight sides parallel with the axis of the ring and having its edges spaced substantially the distance of the diameter of said roller, then broaching from one side to the other side of the ring along the sides of said openings, slot-like openings of a circumferential length larger than the diameter of said roller, and then shaving the material between the sides of the ring axially from said slot-like openings to form opposed roller pockets of substantially the curvature of the roller, substantially the entire curved surfaces of the opposed pockets contacting with the curved surface of the roller when the roller is sprung into said pocket between the straight sides of the opening spaced the diameter of the roller on one of the sides of the ring.

The invention will be more fully described hereafter, embodiments will be shown in the drawing, and the invention will be finally pointed out in the claims.

In the accompanying drawing:

Figure 1 is a perspective view of the improved roller retainer, with the outer ring of the roller bearing partly broken away made in accordance with my method;

Figure 2 is a perspective view, in an enlarged form, of a roller pocket in the retainer;

Figure 3 is an end view of a ring which later forms a retainer but in its initial state, immediately after the circular holes have been drilled into the initial blank and before broaching;

Figure 4 is a partial circumferential view taken on line 4—4 of Figure 5, after the form shown in Figure 3 has been subjected to broaching;

Figure 5 is a view of the ring or retainer shown

in Figure 3 after it has been subjected to the process of broaching;

Figure 6 is a partial circumferential view with a plan view of the tool used for shaving;

Figure 7 is a detail of a part of the retainer shown in Figure 5 with a tool therein in its initial position, ready to be moved downward in the direction of the arrows shown;

Figure 8 is a fragmentary front view of Figure 6 after the tool has done its work and has been removed therefrom;

Figure 9 is another fragmentary perspective view of the retainer with a roller seat shown therein from another direction of view than the perspective of Figure 2;

Figure 10 is a diagrammatic view of a part of the retainer after it has been formed by the process described just as the roller is ready to be snapped into the pocket of the retainer;

Figure 11 is a similar diagrammatic view as shown in Figure 10, but with the roller seated for operative purposes within the seats;

Figure 12 is a diagrammatic side view of a form using oiling channels; and

Figure 13 is a diagrammatic view of a modified form of surface for the rolling member.

Similar characters of reference indicate corresponding parts throughout the various views.

Referring to the drawing, and more particularly to Figures 3 to 8, a solid ring forming the basis of a retainer is shown in Figure 3, provided in any suitable manner with circular openings 12. This ring is then subjected to a well known broaching action, which is so carried out that the diameter of the hole 12 indicated by the double headed arrow 13 in Figure 3, is maintained as shown by the double pointed arrow 13 in Figure 5. The central line or median line of the ring passes through the double headed arrow 13.

Above and below this diameter 13 the material of the retainer 14 is provided by the broaching action with enlarged cutouts 15 and 16, 15 being the upper one, and 16 the lower one, the material of the retainer adjacent to 12 being also removed so that the distance between the upper face 17—A and the lower face 18—A (Figure 2) is slightly greater than the length of the roller to be used.

After the retainer has been provided with the desired number of cutouts of the configuration just described, and which are generally indicated by the character 20 and of the desired number to correspond to the number of rollers intended to be held by the retainer and which number varies from case to case, a tool 21 shown in plan Figure 6 and in elevation partly in section

in Figure 7, is inserted to the enlarged portion 15-15 of the cutout 20. This tool 21 has a holding portion 22 and then enlarges by lateral curved portions 23, the curved portions corresponding to the curvature of the rollers or to whatever other contour is desired, the tool then merging into a narrower end portion 24 as shown in Figure 6.

When a tool of this character has been inserted into the enlarged portion 15-15 of the cutouts 20, it is then moved downward in the direction of the arrows 25 shown in Figure 7, and in consequence the metal of the retainer is removed along the portions extending from the shoulder 17 to the shoulder 18 until the tool enters the enlarged portions 16-16 of the cutouts 20, whereupon it is removed by being withdrawn from the retainer. This downward movement of the tool 21 from shoulder 17 to shoulder 18 and below the shoulder 18, gives the material between 17 to 18 a curvature corresponding to the curvature of the contour of the tool, which is like that of the roller or other desired contour. Any metal such as results from the removal of the portions of the retainer to provide these opposed contour surfaces, drops into the lower enlarged portion 16-16 and may readily be removed from the retainer.

In Figure 6 there is shown in plan view the initial lines which resulted from the broaching, namely, the lines 21, and outwardly of each pair of lines 27 there is shown contour lines 28 resulting from the operation of the tool 21. The entrance of tool 21 into the cutouts 15 or 16 is determined by a suitable abutment generally indicated by 30 in Figure 6, so that with the insertion of the tool into the respective cutouts 15 or 16, the insertion is always the same and the contour surfaces 23 are in proper relation to the parts of the retainer between the shoulders 17 and 18 so that the contour obtained by the operation of tool 21 is exactly the same. In the foregoing description the word downward was used in relation to the drawing sheet. The movement of the tool 21 is axial. The tool 21 is inserted either into the slots 15-15, or into the slots 16-16, and then moved axially of the ring 14, in one or the other direction. If the tool is inserted in 15-15 then the axial movement of the tool is towards 16-16. If the tool is inserted in 16-16, then the axial movement of the tool is towards 15-15.

After the seats for the rollers have thus been brought to proper contour, a roller 35 is placed upon the outer circumference of the retainer 14 as shown in Figure 10, the diameter 36 of the roller 35 being larger than the circumferential length along the periphery of the retainer 14 from point 37 to point 38 of the retainer 14, and as a result of this very slightly larger diameter, the roller will rest upon these points 37 and 38 and can be inserted only into the roller pockets 39 and 40 by a gentle pressure applied to the roller. Such a gentle pressure applied will cause the points 37 and 38 to yield, due to the inherent elasticity of the metal of the retainer when such metal is present to such a fine edge as the node of the two curved surfaces, namely the exterior peripheral curvature and the contour forming the pocket of the roller. The metal will thereby give slightly just sufficient to allow the diameter of the roller to pass between the edges 37 and 38, and the roller will thereby enter into its pocket. The inherent resiliency of these edges 37 and 38 will cause the metal to spring back into

its initial position and will thereby hold the rollers in their pockets at seats 39 and 40, as shown in Figure 11.

Where desired, the retainer pocket can be so made that the roller may be assembled into position from the inside instead of the outside of the retainer.

The circumferential line passing through the center 41 of the roller is indicated by line 42.

Thus by a very gentle pressure applied to the rollers, they may be inserted into the seats of the retainer and held therein, and at the same time the curvature of the seats corresponding to the curvature of the rollers giving a full face contour brings about a very high efficiency of the operation corresponding to a decrease in friction. The curvatures need not, however, be the same.

In Figures 2 and 9 there are shown in enlarged form two different views of the roller pockets 28 showing the curvature thereof corresponding to the contour of the tool and to circumference of the rollers. Retainers of this kind may be provided with any number of roller pockets in the embodiment shown in Figure 1, showing 16 roller pockets with the rollers therein, the retainer 14 holding the rollers 35 and the roller bearing shown in Figure 1 being provided with its inner race ring 45 and its outer race ring 46 in the manner well known.

Instead of limiting the motion of tool 21 in respect to its abutment 30, in the manufacture and process, tool 21 can be supported in a stationary position, and a slide holding the retainer with its cutouts 20 can be moved to and from the tool, a stop being then provided for the slide. The tool can be governed by a spring so as to hold the tool normally against an adjustable stop for height, so that the normal shaving portion of the tool will enter into the upper enlarged portion 15-15 and after the tool has been pressed downward or axially to carry out the shaving operation and reaches the enlarged portions 16-16, the retainer can be withdrawn from the tool by moving its supporting slide, and the sliding action will then move the tool from its lowermost position back to its uppermost position.

A shaving tool could be used in the roller retainer pocket, to provide an oil groove which under some conditions is an advantageous feature. Such a bearing is shown in Figure 12. The shaving tool has a projecting portion which in the shaving operation cuts oil grooves 50, each laterally of the roller pockets 51 and axially of the rolling member. The grooves 50 are shown in Figure 12, approximately on the pitch circle, but may be placed anywhere along the curvature. Other contours of roller pocket walls may be made by the same method, and the configuration of the tool would be modified accordingly.

Roller bearings are also made with rollers having a length considerably greater than the diameter, or in some cases, the length is less than the diameter, and the retainer may be made for such variations.

The invention is also applicable to ball or needle bearings.

Instead of a cylindrical surface, a curved surface with different radii of curvatures can be used, or the surface may have straight parts angularly disposed to each other as shown in Figure 18, in which the angular surfaces 60 and 61 make each a point or line contact 62 with the rolling member 35.

From the foregoing description, it will be clear

that a very simple method of operation has been provided by means of which the roller pockets in a retainer may be made, and after being made the metal of the retainer is not distorted and subjected to a deteriorating action, or rupture.

I have described the invention in connection with the embodiment shown, but it is clear that changes may be made therein without departing from the spirit of the invention as set forth in the appended claims.

This is a divisional application of my copending application Serial No. 314,779, filed January 20, 1940.

What I claim is:

1. A method of making roller bearing pockets in a solid ring retainer, which consists in first drilling circular openings radially from one side to the other side of said solid ring spaced circumferentially along the central line of the ring having a diameter equal to the diameter of the roller for which the retainer is intended, then broaching the ring to form the circular opening into an opening having straight sides parallel with the axis of the ring and having its edges spaced substantially the distance of the diameter of said roller, then broaching from one side to the other side of the ring along the sides of said openings, slot-like openings of a circumferential length larger than the diameter of said roller, and then shaving the material between the sides of the ring axially from said slot-like openings to form opposed roller pockets of substantially the curvature of the roller, substantially the entire curved surfaces of the opposed pockets con-

tacting with the curved surface of the roller when the roller is sprung into said pocket between the straight sides of the opening spaced the diameter of the roller on one of the sides of the ring.

2. A method of making roller bearing pockets in a solid ring retainer, which consists in first drilling circular openings radially from one side to the other side of said solid ring spaced circumferentially along the central line of the ring having a diameter equal to the diameter of the roller for which the retainer is intended, then broaching the ring to form the circular opening into an opening having straight sides parallel with the axis of the ring and having its edges spaced substantially the distance of the diameter of said roller, then broaching from one side to the other side of the ring along the sides of said openings, slot-like openings of a circumferential length larger than the diameter of said roller, and then shaving the material between the sides of the ring axially from said slot-like openings to form opposed roller pockets of substantially the curvature of the roller, substantially the entire curved surfaces of the opposed pockets contacting with the curved surface of the roller when the roller is sprung into said pocket between the straight sides of the opening spaced the diameter of the roller on one of the sides of the ring, and controlling said shaving for each pair of pockets so that every pocket has the same curvature, the slot-like openings permitting the entrance and exit of the shaving tool.

CARL A. BADEN.
